UNITED STATES PATENT OFFICE

CLIFTON S. WILLIAMS, OF WILKINSBURG, PENNSYLVANIA, ASSIGNOR TO WESTINGHOUSE ELECTRIC & MANUFACTURING COMPANY, A CORPORATION OF PENNSYLVANIA

INDUCTION FURNACE

Application filed August 14, 1929. Serial No. 385,791.

My invention relates to electric furnaces and more particularly to electric furnaces of the induction type.

An object of my invention is to provide a relatively simple, inexpensive and highly efficient heating structure for an induction furnace.

Another object of my invention is to provide a novel coil structure for an induction furnace of the surrounded-pool type.

In practicing my invention, I provide a crucible for containing metal or material to be melted, which is surrounded by a pair of energizing coils, the axes of which are symmetrically, oppositely, and angularly inclined relative to the longitudinal axis of the crucible, in such manner as to leave uncovered the top part of the crucible.

In the single sheet of drawings,

Figure 1 is a view in vertical section, taken on the line I—I of Fig. 2, of a furnace embodying my invention;

Fig. 2 is a top plan view of the device shown in Fig. 1;

Fig. 3 is a view, in vertical section, taken on the line III—III of Fig. 4, of a modified form of furnace embodying my invention, and

Fig. 4 is a top plan view of the furnace shown in Fig. 3.

Referring more particularly to Figs. 1 and 2 of the drawings, I have there shown an induction furnace of the surrounded-pool type, as embodying an outer open-top casing 11 which may be substantially rectangular in form but may also be of some other shape, if desired. The casing 11 may be made either of metal or of a suitable electric-insulating material, as may be found desirable. Within the outer casing is located a crucible 12 which, as shown, is substantially square in lateral section and is provided with a pouring spout 13 at its upper edge. The crucible may be made of any suitable refractory material usually employed for such purposes.

I have shown the bottom of the crucible as provided with lateral extensions 14, constituting supporting lugs, and the crucible 12 rests upon two spaced blocks 16 of a suit-

able refractory electric-insulating material, and the blocks 16 rest upon a similar plate 17. Short bolts or screws 18 and 19 may be provided to hold the crucible on the blocks and the blocks on the plate, but these details are shown for illustrative purposes only and constitute no particular part of my invention.

Two sets of coils 21 and 22 are provided, each including a plurality of turns, the turns of the respective coil parts or sections being substantially identical, and the longitudinal axes of the two parts of the energizing coils being symmetrically, oppositely, and angularly inclined, relative to the longitudinal axis of the crucible, in substantially the manner shown in Fig. 1 of the drawings.

Electrical connections (not shown) are provided between the ends of the two coils to connect them in either electrical series relation or in parallel-circuit relation, as may be desired, so that the fluxes generated by the coils shall be added to each other. Electric insulating material (not shown) may be provided between the adjacent individual turns of each coil, in a manner well known in the art, to securely hold the coil parts in the positions shown in the drawings.

A laminated structure located between the sides of the crucible 12 and the side walls of the casing 11 may comprise a plurality of sheet-steel laminations 23 which are either individually of hollow rectangular shape or which are built up of abutting or overlapping strips of magnetic material, in a manner well known in the art. Blocks 24 may be provided in the bottom of the casing 11 and blocks 26 may be provided at the top of the laminated structure, both sets of blocks being of electric-insulating material, in order to hold the laminated structure in its proper operative position within the casing. Clamping screws 27, extending through a top wall of the casing, may be provided to hold the laminations tightly in their proper operative positions.

Referring more particularly to Figs. 3 and 4 of the drawings, I have there illustrated a casing 31 substantially the same as cas-

ing 11, and a crucible 32 has substantially the same form as crucible 12 and is supported in substantially the same manner. Two coil parts 33 and 34 are provided, each part being substantially the same as the coil parts 21 and 22.

5 A laminated structure 36 is provided, which is somewhat different from the laminated structure 23 of Figs. 1 and 2, the individual elements thereof being of substantially U-shape and laminated in a direction coinciding with the longitudinal axis of the crucible 32.

10 Means for supporting the crucible 32 comprise a plate 37 of electric-insulating material, a superposed plate 38 between which extends the intermediate portions of the laminated members 36, and blocks 39 of electric-insulating material, held by screws or by any other suitable means. The individual turns of the parts 33 and 34 of the energizing coil may be spaced from each other by suitable electric insulating material (not shown) and from the side walls 20 of the crucible by a plurality of strips 41.

15 It may be noted that the coil provided for effecting a transfer of electric energy into material 42, shown in the respective crucibles in the form of molten metal, has a part of each turn of each coil portion located not only at one side of, but also below, the crucible. That part of each turn located laterally of the crucible is adjacent to the top portion thereof, and it may also be noted that 25 the shape of each turn is substantially rectangular. The top of the crucible is left open or uncovered and, with the positions of the coil parts, as shown, extending laterally from that diameter of the crucible which extends through the pouring spout 30 13, this pouring spout will be free and clear.

20 The device embodying my invention thus provides a relatively simple and highly efficient coil structure, each turn of each coil part being the same as the other turns and each turn being located adjacent to two sides of the crucible, whereby a better transfer of electric energy into the material to be heated is effected. I have shown the usual trunnions on the casings for suitably mounting the furnace to permit of tilting 25 it to pour the molten metal.

25 Since various modifications may be made in the device embodying my invention without departing from the spirit and scope thereof, I desire that only such limitations shall be placed thereon as are imposed by the prior art or are set forth in the appended claims.

30 I claim as my invention:

1. In an electric induction furnace, in combination, a crucible and a two-part energizing coil for said crucible, the longitudinal axes of the two parts of the coil being 35 symmetrically and oppositely inclined angu-

larly with respect to the longitudinal axis of the crucible and intersecting the same above the bottom of the crucible.

2. In an electric induction furnace, in combination, an open-top crucible and an energizing coil therefor, the bottom portion of a turn of the coil being located below the crucible and the top portion of a turn being located laterally of the crucible.

3. In an electric induction furnace, in combination, an open-top crucible and an energizing coil for said crucible having a plurality of coplanar turns of the same shape and dimensions, the lower portion of a turn of the coil being located below the crucible and the top portion of a turn being located laterally of the crucible.

4. In an electric induction furnace, in combination, an open-top pot-type crucible and a two-part energizing coil for said crucible, each part having a plurality of coplanar turns of substantially rectangular shape and of the same size, the axes of the coils being symmetrically and oppositely inclined angularly relative to the axis of the crucible.

5. In an electric induction furnace, the combination with a crucible having a pouring spout, the axis of the crucible being normally vertical, and a two-part energizing coil for said crucible, the lower portions of the turns of the respective parts of the coil being located closer together than the upper parts thereof and the pouring spout of the crucible being located at its upper end and between the spaced upper portions of the two parts of the coil.

6. In an electric induction furnace, the combination with a vertical-axis crucible having a pouring spout, and a two-part energizing coil for said crucible, each part having a plurality of turns and the axes of the turns of each part being oppositely inclined angularly relative to the axis of the crucible, the spout extending laterally of the crucible between the spaced parts of the coil.

7. In an electric induction furnace, in combination, a crucible, an energizing coil each turn of which is located adjacent to two different faces of the crucible, and laminated material outside of said coil to provide an incomplete magnetic circuit for flux generated by said coil.

In testimony whereof, I have hereunto subscribed my name this 30th day of July, 1929.

CLIFTON S. WILLIAMS.
